(57) **CLAIM**

The ornamental design for a wearable computer, as shown and described.

DESCRIPTION

FIG. 1 is a front perspective view of a wearable computer design showing my new design.

FIG. 2 is a rear perspective of the wearable computer.

FIG. 3 is a front view of the wearable computer.

FIG. 4 is a rear view of the wearable computer.

FIG. 5 is a left side view of the wearable computer.

FIG. 6 is a right side view of the wearable computer.

FIG. 7 is a top view of the wearable computer; and,

FIG. 8 is a bottom view of the wearable computer.

The broken lines in the drawings illustrate portions of the wearable computer that form no part of the claimed design.
